PACKING MECHANISM

Curtis Darwin Rice, Omaha, Nebr., and Glenn Gordon Cook, Babylon, N. Y., assignors to Colgate-Palmolive-Peet Company, Jersey City, N. J., a corporation of Delaware

Application March 28, 1946, Serial No. 657,789

10 Claims. (Cl. 226—14)

1

This invention relates to apparatus for efficiently packing a plurality of packages into a larger shipping case or container or the like with a minimum of effort by human attendants and particularly to guide and control mechanism for handling the packages as they are accumulated and as they are being placed in the container.

In its preferred embodiment the invention will be described as used for packing packages of powdered soap which have been previously individually filled and sealed at an automatic or other suitable filling machine within a larger shipping container in which the packages are to be distributed to the wholesale and retail trades. It will be understood, however, that the invention is not so limited and may be applied to the filling of any containers with a plurality of packages for shipping and like purposes. In general, the invention is designed to keep the packing of such containers entirely under control of an operator, but at the same time it provides such automatic operation and control that the manual labor of the operator necessary for each filling operation is reduced to a minimum, whereby the operator maintains a maximum of efficiency during the entire working day.

It is therefore a major object of the invention to provide a novel semi-automatic apparatus for filling a shipping container or the like with a plurality of smaller packages.

It is a further object of the invention to provide a novel associated feed guide or tunnel and power-driven pusher apparatus for positioning a predetermined number of packages in a group before the mouth of an open container and for pushing said group of packages as a unit into the container.

It is a further object of the invention to provide an associated power-operated conveyor and package pusher mechanism operable in timed relation for accumulating a predetermined number of packages before the open mouth of a shipping container or the like and then pushing them en masse into the container.

A further object of the invention is to provide a novel sub-combination device consisting of a special funnel-shaped tunnel and associated package stop device for use in a container packing apparatus.

It is a further object of the invention to provide a novel pusher device and operating and control mechanism therefor for thrusting a plurality of packages as a group toward the open mouth of a shipping container or the like.

2

It is a further object of the invention to provide novel correlated mechanisms rendered operable by a suitable manual control and then actuated by accumulation of packages before a feed tunnel for operating a package pusher device at said tunnel.

It is a further object of the invention to provide novel apparatus for holding a large shipping container or the like positioned to receive a plurality of smaller packages before the mouth of a feed tunnel, and novel release mechanism whereby the weight of the container when filled with packages is sufficient to cause it to drop away from said tunnel.

Further objects of the invention will presently appear as the description proceeds in connection with the appended claims and the annexed drawings wherein:

Figure 1 is a generally isometric front view of a container packing apparatus according to a preferred embodiment of the invention, illustrating especially the feed tunnel through which the package groups are inserted into the open mouth of the container, and also illustrating in lowered position the device for supporting the container before the open mouth of the tunnel;

Figure 2 is another substantially isometric and generally diagrammatic view taken from the side end of the conveyor and looking to the right of Figure 1, illustrating also the tunnel and associated container support, the latter being shown in elevated position with a container in dotted lines, and also illustrating details of the pusher operating mechanism;

Figure 3 is a top plan view of the apparatus of Figure 1, illustrating especially the relation and stroke of the pusher device relative to the conveyor and the feed tunnel;

Figure 4 is a front elevation of the apparatus illustrated in Figure 1, further illustrating the semi-automatic controls for the pusher mechanism, as well as the release device for the container support;

Figure 5 is a substantially isometric view illustrating the sub-combination of the special feed tunnel through which the packages are fed in groups into the open mouth of the container and the stop wall which projects over the conveyor;

Figure 6 is a substantially diagrammatic view of the operating and control mechanism for the pusher as viewed apart from the other mechanism of Figure 1, illustrating details of the operating linkage for both the package contacting and the manual controls for actuating the pusher; and

Figure 7 is a partly diagrammatic view illustrating details of the container support apart from the remainder of the apparatus of Figure 1, and especially illustrating details of the holding and release mechanism therefor.

In general our invention consists in the provision of means for accumulating a plurality of packages as a group before the open mouth of a suitable feed tunnel, thereby aligning them with the open mouth of a suitably held container, a semi-automatic pusher device set in action by the operator whereby the accumulated packages may be pushed as a group through the tunnel toward the container, and a container support which is so balanced that its own weight drops it away from the tunnel when it is filled with a predetermined number of packages. In the illustrated specific embodiment of the invention, packages are continuously delivered to the packaging station on a power operated conveyor, and the pusher is dually controlled, being set in operation manually by the operator and then automatically actuated by contact of a package with a suitable trigger disposed in the path of the packages being accumulated before the tunnel to complete its cycle. The invention also contemplates as a further sub-combination a novel support for the container to be filled with the packages whereby the container is releasably held with its open mouth aligned with the tunnel, and a release device of such nature that when the container is filled it automatically drops away from the tunnel.

Referring now mainly to Figures 1 and 2, packages of powdered soap, which are in this instance rectangular cardboard boxes, are carried by an endless belt conveyor 11 in the direction of the arrow in Figure 1 toward a packing station provided with a suitable feed tunnel device indicated at 12 and later to be described in detail. Endless conveyor 11 may be of any conventional type mounted on a suitable platform structure 13 which is supported rigidly on the floor by upstanding legs 14. Preferably conveyor 11 terminates at the packing station beyond tunnel 12 as will appear.

The packages usually arrive from the package filling machine on belt 11 in a single row as at bottom row 16 in Figure 1. In the illustrated embodiment of the invention, I find it desirable to station a human operator at the packing station to stack the packages entering the packing station in a double row on the conveyor, as illustrated by the top row 17 in Figure 1. Tunnel 12 is of such height as to accommodate the double row of packages. The reason for this arrangement is that, in the particular embodiment of the invention herein described, the container to be filled is of such size as to accommodate two rows of packages in each layer. Obviously any number of vertical rows of packages can be provided depending on the size of the container to be filled.

Tunnel 12, as illustrated in detail as in Figures 4 and 5, is a hollow open-ended, sheet metal, generally rectangular cross-section member. Its bottom wall 18 is smooth and flat and preferably horizontal and its farther vertical side wall 19 is also smooth and flat and disposed at right angles to wall 18. The opposite side and top walls 21 and 22, respectively, converge outwardly rearwardly whereby the tunnel provides an effective funnel for passing a group of packages toward the mouth of the shipping container. The open entrance mouth of tunnel 12 is thus preferably

slightly larger than the cross-section of the package group to be passed therethrough whereas the front discharge mouth of tunnel 12 is substantially the same size as the opening in the top of the container to be packed.

Rigidly and preferably integral with vertical side wall 19 of tunnel 12 is a rearwardly projecting vertical stop wall 23 which as illustrated in Figure 2 extends across the top of the conveyor belt 11 to prevent packages from passing the packing station and dropping off the end of the conveyor, and wall 23 is provided with a recessed portion 24 at its lower rearward corner to accommodate a movable package control trigger as will later appear. Tunnel 12 is also provided on its top wall with a plurality of spring clips 25 which as illustrated in Figure 2 are adapted to secure the top flap of an open-ended container, the other flaps extending over the other tunnel walls, and thereby aids in positioning the container with respect to the tunnel during packing.

Tunnel 12 is preferably rigidly secured to frame 13 as by bolting, riveting or some other suitable manner stationarily locating it in such position that the passage therethrough is perpendicular to the path of conveyor belt 11. Stop wall 23 preferably projects across the entire width of belt 11.

Container support

The container for receiving the packages indicated at dotted lines at 26 in Figure 2 and a supporting device therefor comprises a sturdy forwardly extending bar 27 which has its front end rigid with a bracket 28 fixed upon a cross shaft 29 journaled at opposite ends on rigid frame members 31 extending forwardly from frame 13. Support bar 27 is shown elevated for packing in Figure 2, and in its lower position in Figure 1. At its rear end, bar 27 has rigidly secured thereto an upstanding post 32 adapted to engage the bottom of container 26 and maintain the bottom flaps closed. Just rearwardly of bracket 28, arm 27 has secured thereto an upstanding member 33 provided with a flat top plate 34 adapted to support the underside of container 26 when the latter is in position to be filled before the tunnel.

As illustrated in Figure 7, shaft 29 has rigidly secured thereto a stop member 35 in the form of a ratchet disk having a peripherally open radial stop shoulder 36. Bracket 28 is also rigid with shaft 29 and disk 35. Disk 35 is resiliently connected by a coiled torsion spring 37 concentric with shaft 29 to stationary terminal 38 of one frame member 31 whereby spring 37 as indicated by the arrow in Figure 7 constantly urges counterclockwise rotation of shaft 29 in Figure 7 in counterbalancing relation to the offset weight of bar 27 and any container supported thereby.

Forwardly of shaft 29 and parallel thereto is a rock shaft 39 likewise journaled in frame members 31 and on which is rotatably mounted the lower end boss 41 of a container support release lever 42 which extends laterally and upwardly to terminate in a handle 43 within easy reach of the hand of an operator standing in the package stacking position beside the apparatus. Boss 41 is resiliently connected to a stationary abutment 44 on a frame member 31 through the medium of a coiled torsion spring 45 concentric with shaft 39 and which has its opposite ends anchored in boss 41 and abutment 44, whereby spring 45 tends to rock shaft 39 clockwise in Figure 7 and maintain lever 42 in the upright position of Fig-

ure 1 and to return the lever to that position whenever the operator releases it.

Extending forwardly from boss 41 is a rigid projection or dog 46 which is adapted to engage stop shoulder 36 of disk 35 and thereby hold disk 35 and shaft 29 against counterclockwise rotation. The rear end of bracket 28 is connected above the level of shaft 29 by means of an elongated tension spring 47 to a suitable anchor on frame 13, whereby spring 47 tends to pull bracket 28 and bar 27 toward the upright position illustrated in Figure 7. Spring 47 is of considerable strength and is capable of swinging support 27 and an empty container thereon from the lowered position of Figure 1 to the elevated position of Figure 2. When support bar 27 has been lowered to the position illustrated in Figure 1, engagement of projection 46 with stop shoulder 36 on disk 35 prevents spring 47 from rocking shaft 29 counterclockwise in Figure 7 and prevents raising of the container support to the upright position of Figure 2. This is the normal operative starting position of the apparatus. Spring 45 maintains dog 46 against shoulder 36 when support 27 is elevated, and the cylindrical periphery of disc 35 prevents rocking of dog 46 beyond the ratchet when released. As will appear later in the description of operation of this apparatus, when lever 42 is rocked counterclockwise to release stop shoulder 36 from dog 46, spring 47 rocks bracket 28 and shaft 29 counterclockwise in Figure 7 and thereby raises support bar 27 to its horizontal position where it is maintained by spring 47 during the container filling operation.

On the floor adjacent and below support 27, a suitable roller conveyor 48 is tied to frame 13 as by stake 49 and adapted to receive the filled container when the latter drops thereonto under conditions to be described.

Pusher mechanism

The function of the pusher mechanism is to push a plurality of packages as a group through the tunnel 12 into the open mouth of the container 26 which is supported on the above described container support. Referring to Figures 2, 3 and 6, the pusher comprises essentially a flat vertical plate 51 which is disposed just above the conveyor parallel to the path of movement of the packages on conveyor 11 and has a front surface area of sufficient extent to engage all of the packages accumulated before the open end of tunnel 12 so that movement of the pusher plate 51 at right angles to the path of the conveyor will push all of the packages as a group into the tunnel.

To permit this movement at right angles to the path of the conveyor, pusher plate 51 as illustrated best in Figure 6 is supported on rearwardly extending posts 52 connected by uprights 53 to a flat platform 54 which has its opposite sides slidably mounted on suitable parallel slides 55 and 56 rigidly mounted on frame 13. Mechanism for controllably reciprocating platform 54 and plate 51 between the dotted and full line positions illustrated in Figure 3 will now be described. The stroke of plate 51, which at the start of operation, is normally in the full line position illustrated in Figure 3, is preferably equal to the distance it is desired to move each package toward the bottom of the container on support 27.

Referring now to Figure 6, the lower end of platform 54 is pivotally secured as at 57 to the upper end of a long operating lever 58 which is

pivoted adjacent the floor on frame 13 at 59 and rockable in a plane parallel to the desired direction of movement of plate 51. Lever 58 is connected to suitable mechanism for selectively rocking lever 58. This mechanism comprises a link 61 which is pivotally connected at its front end at 62 to lever 58 and is pivotally connected at its other end 63 to a crank arm 64 which is loosely journaled on a shaft 65 suitably mounted beneath frame 13. Shaft 65 is constantly driven by a suitable power means so that it rotates continuously, and a toothed ratchet wheel 66 rigid with shaft 65 is thereby constantly rotated. As indicated by the arrow in Figure 6, shaft 65 rotates in a clockwise direction. Beyond pivot 63, crank 64 has pivotally mounted thereon at 67 a pawl 68 which is resiliently urged by a coiled spring 69 toward engagement with the teeth of ratchet wheel 66.

Adjacent the ratchet assembly extends a pair of control fingers 71 and 72 for determining engagement of pawl 68 with ratchet 66. Fingers 71 and 72 are disposed on diametrically opposite sides of ratchet 66 and are rigid respectively with concentric rods 73 and 74.

As illustrated best in Figures 3 and 6, outer hollow rod 74 which is suitably supported for rocking on frame 13 is provided with a rigid radial arm 75 which is pivotally connected by a link 76 to a manually operable lever 77 pivoted on the underside of frame 13 so as to be conveniently accessible to the operator who is stacking the packages and operating release lever 42. Lever 77 is biased to return to its illustrated position by spring 78.

The inner rod 73 projects through rod 74, and beyond the latter is provided with a rigid radial arm 81 which is pivotally connected at 82 to an elongated link 83 pivoted at 84 beneath frame 13 to a horizontal lever 85 rigid with the lower end of a short vertical pivot post 86. Post 86 is suitably journaled in an upright pivot on the frame 13 and rigid therewith at its upper end is a horizontally swingable trigger 87 which is adapted to occupy the space 24 below plate 23 and be contacted by the front side of the foremost package positioned before the tunnel.

Trigger 87 is formed with an arcuate portion 88 which extends through the recess 24 somewhat inwardly of stop wall 23 as illustrated in Figure 3, so that it will be abutted and moved by a package in bottom row 16 when the latter has been conveyed before the tunnel. Normally trigger 87 and its shaft 86 are urged to rotate in a clockwise direction in Figure 3 by means of a bias coil spring 89 which is anchored at one end on the frame 13 and at the other end on trigger 87. Spring 89 normally retains trigger 87 in its inner limit position.

It will be seen that rocking of either lever 77 or trigger 87 about their respective pivots, either by the action of the operator or by contact of a package with trigger 87 will selectively actuate fingers 71 or 72 to control engagement of pawl 68 will ratchet 66. In the start of actual operation, as will later be more completely described, pawl 68 is held away from ratchet 66 by finger 72 and when the operator desires to activate the pusher, he rocks lever 77 to remove finger 72 from pawl 68 and allow spring 69 to move pawl 68 into driving engagement with ratchet 66 so that crank arm 64 is driven by shaft 65. After one-half revolution of shaft 65, finger 71 engages and removes pawl 68 from driving engagement with the pawl. This is substan-

tially repeated in reverse when trigger 87 is moved to release pawl 68 from finger 72.

The mechanical association of the parts is such that a half revolution of ratchet 66 in driving engagement with crank arm 64 is sufficient to move pusher 51 the full distance between the dotted line and full line positions of Figure 3.

Operation

In operation, the operator stands at the corner of the apparatus adjacent the packing station as illustrated in Figure 1 where she may stack boxes from the incoming row 16 into a double row 16, 17, as also illustrated in Figure 1. At the beginning of the operation, the pusher is in the full line position illustrated at Figure 3. In this position it will be observed that the vertical side plate 50 of the pusher is disposed directly in the path of the boxes moving toward it on the conveyor 11 and thereby prevents entry of the boxes into the space before the mouth of tunnel 12 until the operator is ready for such to take place. Thus, the operator has ample time to stack the boxes in double rows outside the packing station and none of the packages may enter the station until she is ready for the container packing operation to take place.

In the illustrated embodiment of the invention, it is desired to move twelve boxes in two vertical rows of six boxes each as a group into the container. Hence, when the operator has assembled that number of packages or more in a dual row before the tunnel, the stop plate 50 preventing the conveyor belt 11 from moving the packages into position before the tunnel and conveyor belt 11 frictionally slipping past the boxes at that point, the operator is now ready to accomplish a container packing operation provided a container is in place on support 27.

Before or after stacking of the boxes, the operator picks up a container which is usually open-ended in flat collapsed condition, opens it to tubular form and places it on support 27 with the front flaps open upward and the rear flaps held closed by upright 32. The support 27 is here held in lowered position by engagement of dog 46 and stop shoulder 36. Then release lever 42 is pushed toward the conveyor to remove dog 46 from the path of stop shoulder 36, thereby enabling main spring 47 and auxiliary spring 37 to rock support 27 and container 26 up to the horizontal position of Figures 2 and 7. The open front flaps of the container are adapted to externally telescope with tunnel 12 and the top flap slides into gripping engagement with the springs 25. When the operator releases lever 42, spring 45 rocks the lever back to its upright position, this movement being stopped by contact of dog 46 with disc 35.

Container 26 is now in position to be packed. Below the conveyor, shaft 65 is continuously rotating but pawl 68 is held out of driving engagement with ratchet 66 by finger 72 as illustrated in Figure 6 so that crank 64 is idle. The operator now trips lever 71 by hand and rocking of lever 71 transmitted through linkage 76 and 75 and rod 74 actuates finger 72 to lift that finger out of the path of pawl 68 to permit spring 69 to move the pawl into driving engagement with ratchet 66. Crank 64 starts to rotate with ratchet 66, thereby rocking lever 58 through link 61 and sliding pusher plate 51 rearwardly away from tunnel 12.

Crank 64 rotates thus with ratchet 66 for one-half a revolution of shaft 65 and then the drive therebetween is interrupted due to finger 71 which remains in the path of pawl 68 removing pawl 68 from driving engagement with ratchet 66. At this point of drive interruption, pusher plate 51 has been moved back to the dotted line position illustrated in Figure 3, and plate 50 is no longer in the path of the stacked packages on conveyor 11, and the latter now moves the packages toward the right in Figure 3. When the required twelve packages become located before the mouth of tunnel 12, the pusher is now automatically operated to push the twelve packages as a group at right angles to their path of movement on the conveyor directly into the tunnel 12. This automatic operation is determined by contact of the lowermost forward package of the group with trigger 87. When trigger 87 rocks about pivot 86 in response to pressure of that package, it operates through links 85, 83 and 81 and rod 73 to remove finger 71 from its restraining influence on pawl 68 and thereby permit spring 69 to again move pawl 68 into engagement with driving ratchet 66, so that crank arm 64 again moves for another half revolution of shaft 65 in driving engagement with pawl 68. This movement of crank arm 64 is such as to operate link 61 and lever 58 to move pusher plate 51 forwardly toward the full line position illustrated in Figure 3. When shaft 65 has rotated one-half revolution pawl 68 contacts finger 72 which has been moved back into its path by a suitable spring 70 after the operator lets go of lever 71, and pawl 68 is again removed from driving engagement with ratchet 66 to stop movement of the pusher plate which by this time has reached the full line position of Figure 3. This means that the dual row of packages which had been standing on the conveyor at the mouth of the tunnel have now been moved as a group into the tunnel, and the pusher mechanism, having completed a cycle, is ready for the next operation. Advance of the group of packages on the conveyor beyond the tunnel during pusher plate movement is of course prevented by stop wall 23. When the packages have entered the tunnel, trigger 87 and finger 71 reassume their original positions through actuation of return spring 89.

The operator then insures that another group of twelve packages in dual rows is arranged adjacent plate 50, before she once more manipulates lever 71 to start the above described operation of the pusher mechanism all over again. This time, as pusher plate 51 advances to push the group of packages from the conveyor into tunnel 12, the second group contacts the previously advanced group in front of it, and pushes the latter forwardly through the front end of the tunnel into container 26. When the pusher operation is repeated the third time, the forward layer or group of packages is moved into the bottom of container 26 and the second group of packages has also been pushed into the container, thus filling the container with its capacity of twenty-four packages.

The length of bar 27 is such that the filled container 26 exerts a turning force on shaft 29 which now overbalances the combined pull of main spring 47 and auxiliary spring 37, and the support and container together rock about shaft 29 to drop away from tunnel 12 and down to the lowered position of Figure 1. The support is locked in this position by reason of dog 46 re-engaging stop shoulder 35, so that the operator

now has ample time to place the filled container on conveyor 48 and place a new empty container on support 27 ready to start the packing operations over again.

While we have described an operation wherein three strokes of the pusher are required to pack the first container, and two strokes for packing each succeeding container, it will be understood that this may vary depending on the depth of the container and other factors.

We have thus provided a packing device for filling a shipping container or the like with a number of smaller packages which is semi-automatic in its filling operation and requires a minimum of manual labor by attendant or operator while at the same time preserving all of the operations under the full control of the operator. All of the controls are arranged adjacent the hands of the operator whereby she may stand or sit on a stool at the package station and devote her full attention to the packing operation and accomplish the same with maximum efficiency.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore to be embraced therein.

What is claimed and desired to be secured by United States Letters Patent is:

1. In a container packing apparatus, a packing station, a movable conveyor for delivering packages into said station and upon which said packages may be accumulated in desired groups prior to entry into said station, means for holding an open-end container in packing position at said station, means movable transversely of the conveyor for pushing a group of said packages off the conveyor toward said container, means at said station for funneling said so-pushed group of packages into said container, and control means for timing actuation of said pusher with package feed comprising means normally in the path of packages on said conveyor for retarding advance of said packages into said station until a desired group has been accumulated on said conveyor, manually controlled means for activating said pushing means and removing said retarding means from said path, and means controlled by the group of packages moving into said station for actuating said pushing means in its container packing stroke and returning said retarding means to said normal disposition in said path.

2. In a container packing apparatus, means for holding an open-ended container in packing position, a feed guide through which packages are adapted to be pushed into said container, a continuously movable conveyor for advancing said packages into alignment with said feed guide, a pusher transversely movable back and forth across said conveyor adapted to push a group of packages off said conveyor and into said guide with each container packing stroke and a stop member transversely movable with said pusher normally extending across said conveyor in the path of packages on said conveyor to cause and permit accumulation of a group of said packages on said conveyor before permitting them to feed into the path of said pusher.

3. In a container packing apparatus, a package pusher movable between a first and second position for pushing groups of packages toward an open-ended container, means for feeding groups of said packages into the path of said pusher, power means for moving said pusher, a manually operable control for connecting said power means to move said pusher in one direction between said positions, and a package operated control for connecting said power means to move said pusher in the other direction between said positions.
4. In the apparatus defined in claim 3, wherein actuation of said manual control also starts feed of a group of packages into the path of said pusher, and said package operated control comprises a trigger contacted by a foremost package of said group when said group has been positioned in the path of said pusher.
5. In a container packing apparatus, a reciprocable pusher device movable between a normal forward position and a rearward position, a conveyor for moving packages into the path of said pusher, power means for moving said pusher, manually controlled means for actuating said power means to move said pusher from its forward position to said rearward position, and package operated means for actuating said power means to move said pusher from said rearward position to said forward position in a container packing stroke.
6. In the container packing apparatus defined in claim 5 stop means on said pusher extending across said conveyor in said forward position of the pusher, said stop means being removed to permit advance of said packages into the path of said pusher when the latter is retracted to its rearward position, and means for stopping said advancing packages in the path of said pusher prior to said container packing stroke of said pusher.
7. In the container packing apparatus defined in claim 5 said package operated means comprising a trigger adapted to be contacted by a foremost package when a desired number of packages are disposed in said path.
8. A feed tunnel subassembly for a packing device comprising a generally rectangular hollow frame having a flat bottom wall and one vertical side wall, and an integral rearwardly projecting stop wall extending in alignment with said vertical side wall.
9. In apparatus for packing a container with a plurality of smaller packages, a packing station, means for feeding packages into said station, a package pusher device in said station normally disposed in the path of said packages being fed into said station, means for moving said pusher device out of said path to permit entry of a group of packages into said station and means responsive to introduction of a group of packages into said station for moving said pusher device back across said path to push said group of packages toward a suitably held container.
10. In a container packing apparatus, a movable conveyor, a packing station, a funnel and a container support at one side of said conveyor at said station, a pusher disposed above said conveyor at said station normally in the path of articles on said conveyor so as to prevent entry of said articles into said station, manually controlled power driven means for moving said pusher away from said funnel to thereby permit entry of said articles into said station and for maintaining said pusher in its retracted position.

tion until a predetermined supply of said articles is positioned between the pusher and the funnel, means at said station in the path of the articles on the conveyor for arresting said articles between the pusher and the funnel, and means triggered by the leading article fed into said station on the conveyor for moving said pusher across the conveyor toward said funnel in a container packing stroke and for maintaining said pusher above the conveyor until said manual control is again exercised.

CURTIS DARWIN RICE,
GLENN GORDON COOK.
